UNITED STATES PATENT OFFICE

BALTHASAR VAN DER POL, OF EINDHOVEN, NETHERLANDS, ASSIGNOR, BY MESNE ASSIGNMENTS, TO RADIO CORPORATION OF AMERICA, OF NEW YORK, N. Y., A CORPORATION

DISCHARGE TUBE

Application filed October 19, 1925, Serial No. 63,401, and in the Netherlands January 23, 1925.

This invention relates to discharge tubes comprising an incandescent cathode and two or more other electrodes lying in the same cylindrical surface and has for its object to 5 provide such a construction of tubes of this kind that their manufacture can be easily and exactly effected.

The invention also includes the process according to which these tubes can be manufactured.

The discharge tube according to the invention is distinguished from other tubes in that the grid or grids consist of a number of rings or groups of one or more wire rings or turns 15 lying close to or against each other while the anode when lying in the same cylindrical surface also consists of wire rings or turns which are mutually connected and are located between the groups of the grid.

20 A particularly simple construction is obtained when the group of conductors pertaining to the anode, as well as the group or groups pertaining to the grid or grids, are each assembled into one or more helical windings.

The process according to the invention is characterized in that the rings or turns pertaining to the anode or to the grid or both kinds of rings or turns are laid around a 30 mandrel which is removed again after the anode and grid portions have been fixed mutually as well as relatively to each other by means of carriers which at the same time may serve as leading-in members, and by means 35 of connecting wires, if any.

According to the invention, if the anode and the grid consist of helical windings, use can be made of a mandrel on the outer surface of which a multiple screw thread is provided 40 and which after the anode and the grid have been wound and fixed, is screwed back out of these members.

In the accompanying drawings, Figure 1 represents an embodiment of an electrode construction according to the invention, and Figure 2 represents a mandrel which can be used for the manufacture of this construction.

The grid according to Figure 1 has been helically wound out of three wires 1, 2 and 3, 50 lying close to and against each other. An

anode wire 4 has been helically wound in the same cylindrical surface between the grid windings and slightly spaced supports therefrom. At their ends the grid wires 1, 2 and 3 are fixed in supports 5 and 6 which are sealed 55 in the pinch (not shown) of the stem of the lamp and either of which may be used to conduct the grid current. The anode wire 4 is supported by supports 7 and 8 to which the same remark applies as that made for the supports 5 and 6.

An incandescent cathode 9 runs axially through the tubular body formed by the wires 1—4 and is supported by the lead wires 10 and 11.

The whole is enclosed or sealed in any known manner in an envelope, such as a bulb 18 consisting wholly or partly of glass, which bulb thereupon is exhausted.

In order to obtain a uniform field it is advisable to choose the pitch of the screw thread so as to be not larger than the radius of the cylinder on which the helix is wound. When using annular anode- and grid portions, the distance between two successive rings of like 75 nature, measured from centre to centre, takes the place of the pitch of a helical grid or anode.

In the manufacture of the electrodes it is advantageous to make use of the mandrel 80 represented in Figure 2. It consists of a cylindrical body 12 of refractory material such as tungsten in order to be able to anneal the anode and the grid on the mandrel. A narrow screw thread 13 and a second wider 85 screw thread 14 which is as deep as 13, are provided in the outer surface of the body 12. Between the two screw threads there remain ridges 15 and 16 which determine the distance between the anode and the grid. At one end 90 the mandrel terminates in a smaller, square portion 17 by which it can be turned. The grid wires 1—3 and the anode wire 4 may be wound simultaneously or successively on the mandrel; they are fixed in the stem of the tube by means of their respective supports 5—6 and 7—8 and then, if desired, annealed,

whereupon the mandrel can be screwed back out of the cylinder. Thereupon a cathode wire 9 can be provided.

It will be obvious that the anode or the grid or both of them, instead of being made from round wires can also be wound from flat wires, in which case the grid may also consist of a single wide flat band and the anode of a narrower one. This will tend to simplify the manufacture.

The amplification factor of a triode being a function of the ratio of the capacities grid-
10 filament and anode-filament, any desired value (provided it is not too large) of the said factor can be obtained by a suitable choice of the ratio between the surface of the grid and that of the anode. In the example
15 illustrated the amplification factor will be about equal to 3.

What I claim is:

1. An electron discharge tube, comprising a straight cathode, an anode consisting of a coil
20 of wire wound in the form of a helix, and a grid consisting of a coil of wire wound in the form of a helix, the two helices being so interwoven that each winding of the anode is adjacent on each side to a plurality of windings
25 of the grid.

2. An electron discharge device comprising a heatable straight cathode for emitting electrons, and two cooperating electrodes in the form of two helices of the same diameter and
30 pitch coaxially disposed to lie in the same cylindrical surface about said cathode with each turn of one helix lying between two adjacent turns of the other helix and the turns of one of said helices being so spaced that a
35 substantially uniform electrostatic field exists between the adjacent turns of said helix when said helix is at normal operating potential.

3. An electron discharge device comprising a heatable electron emitting cathode, an
40 anode and a grid in the form of two helices of the same diameter and pitch and both coaxial with said cathode, the turns of said grid having a greater width than the turns of said anode, and each turn of said anode
45 lying between adjacent turns of said grid.

In testimony whereof I affix my signature at the city of Eindhoven, this 16th day of September, A. D. 1925.

BALTHASAR VAN DER POL.
